UNITED STATES PATENT OFFICE.

LAWRENCE T. THORN, OF HARRISBURG, ARKANSAS.

COMBINED LICENSE-TAG HOLDER AND LIGHT-SUPPORTING MEANS.

Application filed February 19, 1924. Serial No. 693,811.

To all whom it may concern:

Be it known that I, LAWRENCE T. THORN, a citizen of the United States, residing at Harrisburg, in the county of Poinsett and State of Arkansas, have invented certain new and useful Improvements in Combined License-Tag Holders and Light-Supporting Means, of which the following is a specification.

This invention relates to an improvement in holders for license tags and has for its primary object to provide a holder of the character shown and described in my co-pending application, Serial No. 689,281, filed January 29, 1924, provided with means whereby a tail light, rear view light, stop signal, a combination stop signal and tail light, or a reflex light supported in close proximity to said license tag and whereby other supporting means for a light of any one of the before-mentioned forms will be unnecessary.

An additional object is to provide a combined article of the above character wherein the light may be disposed with relation to the license tag, so as to allow the indicia thereon to be illuminated by the lamp bulb within said light.

With the foregoing salient objects in view and others that will appear as the nature of the invention is better understood, the same comprises the novel form, combination, and arrangement of parts hereinafter more fully described, shown in the accompanying drawings, and claimed.

In the drawings, wherein like reference characters indicate corresponding parts throughout the different views:

Figure 1 is a front elevational view of a combined license tag holder and light supporting means constructed in accordance with the present invention, the same being shown as actually in use.

Figure 2 is a rear elevational view thereof.

Figure 3 is a detailed vertical sectional view, taken substantially upon the line 3—3 of Figure 1.

Figure 4 is a detailed vertical sectional view, taken substantially upon the line 4—4 of Figure 3 and looking in the direction of the arrow for more clearly disclosing the relative positioning of a specific form of light supporting means for the present invention.

Figure 5 is a fragmentary perspective view of this specific form of light, and

Figures 6 and 7 are fragmentary perspective views of portions of the said light supporting means and the retaining ring for the light respectively.

Now, having particular reference to the drawings, there is shown in Figures 1, 2, and 3 a specific form of holder for license tags, with which the present light supporting means is to be associated and in these figures the holder for the tag 5 and upper and lower sections 6 and 7. It will not be necessary to fully describe the construction of this holder as the same is clearly shown and described in the before-mentioned pending application. However, it will be necessary to describe somewhat specifically the upper holder section 6 and in this instance, the same comprises a pair of cooperating sheet metal channel bars 8 and 9, each of which is of substantially inverted U-shaped in cross section as clearly shown in the detailed vertical sectional view, Figure 3. The channel bar 9 is adapted for free sliding longitudinally within the channel bar 8 and said first mentioned channel bar is formed at a point adjacent its inner end and upon its top side with a struck out relatively long lug 10 that is adapted for the selective reception within any one of a plurality of cut outs 11 in the upper edge of the sheet metal channel bars 8. The lug 10 fitting within one of the cut out portions 11 serves to provide an adjustable and interlocking connection between the cooperating portions of the channel bars 8 and 9 of the upper frame member, so that its length may be adjusted to receive a license tag of predetermined size, in a manner as clearly set forth in the above mentioned co-pending application.

The present invention contemplates the integral formation upon the lower edge of the front side of said channel bar 8 of a sheet metal plate 12 of a shape preferably as shown in Figures 1 and 2. This piece of sheet metal being bent upwardly so as to provide a vertically disposed supporting bracket for preferably the tail light A of the vehicle.

In order to allow this tail light A to be associated with said bracket 12, the sheet metal plate forming said bracket is formed with a relatively large circular opening 13, with which is rigidly associated, a concentrically arranged open ended tail light receiving casing 14, within which said tail

light A is to be disposed in a manner more clearly shown in Figure 3, it being obvious that in the placing of this lamp the same is disposed within the casing from the front 5 side thereof.

The front end of this light receiving casing 14 is flanged inwardly for providing a circular abutment 15 that engages the usual lens retaining rim of said tail light 10 for preventing the rearward movement of said tail light within said casing.

The bottom side of the light casing 14 is provided with a cut out or slot 16, with which registers the usual light ray opening 15 in the bottom side of said tail light when the same is positioned within the casing for obviously allowing the light rays from the lamp within said light to extend in front of the license tag 5 for allowing the indicia 20 thereon to be clearly viewed at night time.

In order to prevent any rotary movement of the tail light within the casing, and consequent unregistration of the opening within said tail light of the casing, the casing 25 of the light A may be provided at its top side with a channel or depression 16' within which engages a lug 17 pendant from the before mentioned flange 15 of the tail light receiving casing 14.

At the front end of this casing 14, the same is provided with a plurality of bayonet slots 18 with which engage inwardly directed pins 19 carried by a flanged retaining ring 20, that is adapted to be engaged over 35 the front end of said casing 14 and then given a short turn after which the same will obviously be locked upon the casing for thereby preventing the detachment of the same and a consequent displacement of the 40 tail light with respect to its casing.

From the foregoing, numerous advantages of a combination license tag carrier and tail light supporting means of this char-

acter will be at once appreciated by those skilled in the art, and even though I have 45 herein set forth the most practical embodiment of the invention with which I am at this time familiar, it is nevertheless to be understood that minor changes may be made in the invention without departing from the 50 spirit and scope of the appended claims.

Having thus described my invention, what I claim as new and desire to secure by Letters Patent is:

1. A device of the class described comprising an open frame member, a plate formed thereon and extending upwardly therefrom, a cylindrical casing mounted on the plate and extending outwardly therefrom, said casing having an opening formed in the bottom portion thereof adjacent the open frame member, and means cooperating with the outer end of the casing for securing a tail light assembly therein, the opening in the casing being adapted to register with an 65 opening in the tail light assembly to permit the projection of light upon a license tag within the frame member.

2. A device of the class described comprising an open frame member, a plate 70 formed on said frame member and projecting upwardly therefrom, said plate having an opening formed therein above the frame member, a cylindrical casing mounted on the plate and projected through the opening, a rim detachably mounted on the free end of the casing for rigidly securing a tail light assembly therein, and means carried by the casing cooperating with the tail light assembly adapted to hold said tail 75 light assembly in a predetermined relation within said casing.

In testimony whereof I affix my signature.

L. T. THORN.
